UNITED STATES PATENT OFFICE.

MARCELLUS R. SHEDD, OF LANCASTER, NEW YORK, ASSIGNOR TO GOULD COUPLER COMPANY, A CORPORATION OF NEW YORK.

ELECTRICAL REGULATOR.

1,372,097.

Specification of Letters Patent. Patented Mar. 22, 1921.

Application filed November 23, 1915. Serial No. 63,012.

To all whom it may concern:

Be it known that I, MARCELLUS R. SHEDD, a citizen of the United States, and a resident of Lancaster, county of Erie, State of New York, have invented certain new and useful Improvements in Electrical Regulators, of which the following is a specification.

My invention relates to improvements in electric regulators, and more particularly to regulators adapted to vary the resistance of a circuit by means of a carbon pile form of variable resistance, or other type, the resistance of which is varied by variations in pressure thereon. While my improvements are particularly adapted for the regulation of generators in car lighting systems, it will be clear that the invention is capable of use in many other situations.

The main object of the invention is to provide an improved regulator of the carbon pile type, which is extremely sensitive, simple and efficient in construction and operation. Further and more specific objects, features and advantages will more clearly appear from the detailed description given below, taken in connection with the accompanying drawing which forms a part of this specification.

The drawing illustrates a regulator embodying my improvements in one form, certain parts being shown in section, to more clearly illustrate the same, also in connection with an electrical system of distribution, the main features of which are shown diagrammatically.

Referring to the drawing, 1 represents a generator which may be driven at variable speed, to supply the storage battery 2, and lamps or other translating devices at 3. The generator shunt field is shown at 4, having in series therewith a carbon pile resistance 5. A lever 6, pivoted at 7, is adapted to operate upon one end of said carbon pile, and a lever 8, pivoted at 9, is adapted to operate upon the other end of said carbon pile. The ends of the long arms of said levers are mechanically connected together by means of pin 10, secured to the lever 6, operating in a slot 23 in the end of lever 8. The end of the lever 6 is also provided with a knife edge 11 engaging a member 12. The member 12 is provided with apertures in each end. Operating through the aperture on the right hand end of the member 12 is a spindle 13 on a core or plunger 14, adapted

to be pulled up by a solenoid 15, connected in circuit between the generator 1 and the battery 2. A dashpot 16 is provided for damping the movements of the plunger or core 15. The plunger 13 is provided with a pin 17, so that when the plunger 14 is raised, the pin 17 engages the underneath side of the member 12, thereby causing the member 12 to be moved upwardly, which, in turn, by reason of its engagement with the knife edge 11 causes lever 6 to rock about its pivot 7, to increase the resistance of the pile 5. By reason of the pin and slot connecting 10 and 23, lever 8 is also caused to rock about its pivot 9, to operate on the other end of the pile to increase the resistance of the pile at that end simultaneously. A spindle 18 operates in the aperture on the other end of the member 12, the spindle being connected to a core 19, adapted to be pulled up by a solenoid 20, connected across the generator 1. A dashpot 21 is provided for damping the movement of the plunger 19. Spindle 18 is also provided with a pin 22, engaging the underneath side of the member 12, so that upon core 19 being pulled up, pin 22 forces the other end of member 12 upwardly, and in a similar manner, operates both of the levers 6 and 8, which similarly varies the resistance of the pile 5, by operation at both ends. Thus, if the current from the generator exceed a certain value, magnet 15 operates on the member 12, the pin 22 acting as a fulcrum, to actuate both of the lever members 6 and 8, to increase the resistance in the pile 5, to weaken the generator field, to maintain the current output substantially constant. If the voltage tend to increase above the desired value, the voltage magnet 20 will raise its plunger 19, and cause the member 12 to be raised at the other end, the pin 17 acting as a fulcrum, similarly operating both the lever members to increase the resistance in series with the generator shunt field, to keep the voltage within the desired limits. This causes a weakening of the current magnet, permitting the core 14 to drop down into its seat.

While I have described my improvements in great detail and with respect to one embodiment of my invention, nevertheless, it will be understood that many changes and modifications may be made without departing from the spirit and scope thereof in its

105
110

broader aspects. For instance, any other type of resistance medium, whose resistance varies with variations in pressure, may be used instead of the carbon disk type.

- 5 In a copending application filed by me, Serial No. 63011, filed Nov. 23, 1915, I have disclosed the regulator herein claimed as part of the electrical system which is claimed in said application, the claims here-
10 in being confined to the regulator independent of the system in which it may be employed.

Having fully and clearly described my improvements, what I claim and desire to
15 secure by Letters Patent is:

1. An electric regulator having in combination a carbon pile, a lever operating on one end of the pile, a lever operating on the other end of the pile, a member, the move-
20 ment of which actuates both of said levers to vary the resistance of said pile, and two magnets adapted to move said member independently of one another.
2. An electric regulator having in com-
25 bination a carbon pile, a member operating on one end of said pile to vary the resistance thereof, a member operating on the other end of said pile to vary the resistance thereof, a member adapted to move both of said
30 first two mentioned members and two sole-
niods one having a core acting on one end of said third member and the other having a core acting on the other end of said third member, whereby movement of either core
35 acts to vary the resistance of the pile at both ends thereof.

3. An electric regulator having in combination a carbon pile, mechanism operating

said pile to vary its resistance, two elec-
tromagnets, separately movable armatures 40 for said electromagnets respectively, each of said armatures upon being sufficiently at-
tracted by its electromagnet, being adapted to cause said mechanism to operate on both ends of the pile substantially simultane- 45 ously to increase the resistance of said pile at both ends thereof independently of the other armature.

4. An electric regulator having in combi-
nation a carbon pile, a movable head at 50 each end thereof, a pivoted lever connected with each head and a lever actuating member arranged to be independently moved at either of two points thereon to produce a desired movement of both levers without 55 changing the position of the other of said points.

5. An electric regulator comprising a car-
bon pile, two movable heads therefor, an operating lever connected with each head, 60 a member arranged to move said levers simultaneously in response to the movement of a given part of said member, and inde-
pendent means operating upon said member, one at each side of said given part. 65

6. An electric regulator comprising a car-
bon pile, two movable heads therefor, an operating lever connected with each head, 70 a member arranged to move said levers simultaneously in response to the movement of a given part of said member, and mag-
nets operating upon said member one at each side of said given part.

In testimony whereof, I have signed my
name to this specification.

MARCELLIUS R. SHEDD.
